RECEPTACLE CLOSURE

Le Roy E. Gould, St. Paul, Minn.

Application March 14, 1947, Serial No. 734,701

6 Claims. (CL. 220—55)

1

This invention relates to receptacle closures, and more particularly to an improved receptacle cover and locking means therefor.

In certain types of receptacles, such as those used for cooking therein eggs devested of their shells, it is essential that the removable covers for such receptacles tightly seal the same, and it is also desirable that the covers be readily and quickly removable and replaceable for practical use. When the receptacle must be opened when in a hot or cold condition, steps must be taken to prevent injury or discomfort to the hands while handling the receptacle to release and remove its cover.

The present invention is directed to taking care of this problem by providing a receptacle closure in which an upper part of a cover is adapted to be manually turned in one direction relative to a lower part thereof to secure the cover in closing position and in the opposite direction to release the cover, in which a spring is arranged to be placed under compression when the upper part is so turned in the one direction, and in which a manually releasable catch is provided to automatically lock the upper part against turning in the opposite direction after being so turned in the one direction. Thus, upon release of the catch, the spring will automatically turn the upper part in the opposite direction to quickly release the cover for convenient removal without danger of causing injury or material discomfort to the hands of the user due to gripping the receptacle.

A further object of the invention is to provide an improved closure of the above kind which is comparatively simple in construction, easy to use, and efficient in operation.

More specific objects and features of the invention will become apparent from the following description when considered in connection with the accompanying drawings, in which:

Figure 1 is an elevational view of an egg cup and cooker embodying a receptacle closure constructed in accordance with the present invention;

Figure 2 is a top plan view thereof;

Figure 3 is an enlarged vertical section taken on line 3—3 of Figure 2;

Figure 4 is a top plan view of the lower part of the cover forming part of the present closure;

Figure 5 is a bottom plan view of the upper part of said cover;

Figure 6 is an enlarged fragmentary section taken on line 6—6 of Figure 2;

2

Figure 7 is an enlarged section taken on line 7—7 of Figure 2;

Figure 8 is an enlarged section taken on line 8—8 of Figure 2;

Figure 9 is an enlarged section taken on line 9—9 of Figure 2; and,

Figure 10 is an enlarged perspective view of one of the locking bolts.

Referring in detail to the drawings, I have illustrated, by way of example, an egg cup and cooker embodying a closure constructed in accordance with the present invention, said egg cup and cooker being of the type generally disclosed in the U. S. patent to W. R. Hill No. 499,426 of June 13, 1893. As shown, the device includes an egg receptacle or cup 5 having legs 6 or the like for supporting the same in an upright position.

In accordance with the present invention, the receptacle 5 has a mouth portion at its upper end which is formed with an internal annular cover supporting shoulder 7 having a sealing gasket 8 disposed and suitably held thereon. The mouth portion of the receptacle is also formed with an internal annular groove 9 above the shoulder 7.

A cover is provided for the receptacle 5, which cover includes a lower part 10 seated on the shoulder 7, or its gasket 8 and having its upper side even with the top of groove 9. The cover further includes an upper part 11 which is fitted in the mouth portion of receptacle 5 upon the lower part 10. A screw 12 freely passes through a central opening 13 of the lower part 10 and has a threaded upper end portion 14 which is tightly screwed into a threaded socket 15 of the upper part 11 so as to connect the latter to the lower part 10 for rotation relative to said lower part. A pair of diametrically opposed radial grooves 16 are formed in the upper surface of the lower part 10 so as to extend to the edge of the latter, and a locking bolt 17 is slidable radially of the part 10 in each groove 16 thereof and for projection into and retraction from the internal groove 9 of receptacle 5. The upper part 11 is formed in its underside with a pair of elongated eccentric or cam grooves 18 which receive pins 19 that are carried by and project upwardly from the inner end portions of the bolts 17. The arrangement is such that when the upper part 11 is rotated in a clockwise direction as viewed in Figure 2, the bolts 17 will be retracted from the groove 9 so as to release the cover and permit its removal from receptacle 5. The arrangement is also such that when the upper part 11 is rotated in an

anti-clockwise direction as viewed in Figure 2, the bolts 17 will be projected into the groove 9 for locking the cover in closing position. As shown more clearly in Figure 10, the outer ends of the bolts 17 are beveled as at 20 so as to have a camming action for tightly forcing the lower part 10 down upon the gasket 8 when the bolts 17 are projected, thereby effectively sealing the receptacle. The pins 19 also preferably project downwardly from the bolts 17 into elongated radial grooves 21 formed in the lower part 10 within the inner end portions of the grooves 16.

Formed in the upper side of the lower part 10 is an arcuate groove 22, and a similar arcuate groove 23 is formed in the underside of the upper part 11.

As shown in Figure 8, the grooves 22 and 23 are arranged in overlapping relation so that adjacent end walls thereof form spaced shoulders 24 and 25. A helical compression spring 26 is disposed within the overlapped portions of the grooves 22 and 23 with its opposite ends respectively engaging the shoulders 24 and 25. The arrangement is such that when the upper part 11 is rotated in a counterclockwise direction as viewed in Figure 2 so as to project the bolts 17, the shoulders 24 and 25 are moved toward each other so as to place the spring 26 under compression. Accordingly, when the upper part 11 is released, the compressed spring 26 will automatically rotate the upper part 11 in a clockwise direction as viewed in Figure 2 so as to cause retraction of the bolts 17 and release of the cover for free removal. It is pointed out that the frictional resistance to rotation of the lower part 10 offered by engagement of the latter with the gasket 8 is sufficient to overcome the strength of the spring 26 so that the latter will not turn the lower part 10 and will only turn the upper part 11 of the cover.

The lower part 10 also has a further shallow groove 27 within one end of which is secured one end of a leaf spring catch 28 that is normally tensioned to spring upwardly out of said groove 27 although being manually depressible into the latter. The upper part 11 has a further arcuate groove that includes a deep end portion 29 and a shallower end portion 30. This groove 29, 30 is so arranged that when the upper part 11 is turned to a position wherein the bolts 17 are fully projected, the shallow portion 30 will pass the free end of catch 28, thereby permitting the latter to spring upwardly into the deeper groove portion 29 and behind the shoulder 31 formed at the juncture of the portions 29 and 30. When this occurs, the catch 28 effectively holds the upper part 11 against clockwise rotation under the influence of spring 26, thereby securing the cover in locked condition with the bolts 17 projected and the spring 26 under compression. Obviously, therefore, if the catch 28 is depressed to disengage the latter from behind the shoulder 31, the spring 26 will quickly rotate the part 11 in a clockwise direction so as to retract the bolts 17 and thereby release the cover. To facilitate depression of the free end portion of catch 28, a pin 32 is provided which slidably extends through a vertical opening 33 provided in the upper part 11 at the end of the deeper groove portion 29 which is adjacent the shallower portion 30. The lower end of pin 32 has a head 34 which rests upon the free end of catch 28, and the upper end of pin 32 projects above the top of part 11. Thus, by the use of a finger, pin 32 may be depressed so as to depress the free end portion of catch 28 and thereby disengage the latter from

the shoulder 31 so that spring 26 may quickly turn the upper part 11 of the cover in a clockwise direction for causing retraction of bolts 17 and thereby releasing the cover.

The upper part 11 of the cover is provided with a diametric rib 35 on its upper side, and this rib may be employed as a handle for use in rotating the part 11 when projecting the bolts 17 and compressing spring 26. Intermediate its ends, rib 35 may be formed with a slot or opening 36 to receive a suitable tool for use in removing the cover after the latter is released and while the latter is in a hot condition. This slot or opening may be suitable for the introduction of the blade of a table knife or an end of a fork.

From the foregoing description, it is believed that the construction, operation and advantages of the present invention will be readily understood and appreciated by those skilled in the art. Modifications and changes in details of construction are contemplated, such as fall within the scope of the invention as claimed.

What I claim is:

1. In combination with a receptacle having a mouth portion at its upper end formed with an internal annular cover supporting shoulder and an internal annular groove above said shoulder, a cover for the receptacle including a lower part fitted within said mouth portion and seated on said shoulder with its upper side below the upper edge of the receptacle, said cover further including an upper part fitted in said mouth portion upon said lower part and connected to the latter for rotation relative to the same, locking bolts carried by and slidably radially of said lower part for projection into and retraction from said groove to respectively secure the cover in place and to release the same for removal, and means operatively connecting said locking bolts to said upper part so that partial rotation of the latter in one direction will cause projection of said bolts and partial rotation of the same in the opposite direction will cause retraction of said bolts.
2. In combination with a receptacle having a mouth portion at its upper end formed with an internal annular cover supporting shoulder and an internal annular groove above said shoulder, a cover for the receptacle including a lower part fitted within said mouth portion and seated on said shoulder with its upper side below the upper edge of the receptacle, said cover further including an upper part fitted in said mouth portion upon said lower part and connected to the latter for rotation relative to the same, locking bolts carried by and slidably radially of said lower part for projection into and retraction from said groove to respectively secure the cover in place and to release the same for removal, means operatively connecting said locking bolts to said upper part so that partial rotation of the latter in one direction will cause projection of said bolts and partial rotation of the same in the opposite direction will cause retraction of said bolts, a spring arranged between and co-acting with said parts for being placed under compression when the upper part is rotated in the one direction, and means including a manually releasable catch for automatically locking said upper part against rotation in the opposite direction with the bolts projected and the spring under compression, said spring acting to rotate the upper part in said other direction to retract the bolts upon release of said catch.
3. The construction defined in claim 2, where-

in the means for operatively connecting the bolts to said upper part includes cam grooves in the underside of said upper part and pins carried by said bolts and projecting upwardly into said cam grooves.

4. The construction defined in claim 2, wherein said upper and lower parts have overlapping grooves in the adjacent sides thereof, and wherein said spring is arranged in the overlapping portions of said grooves and abuts the adjacent end 10 walls of the latter.

5. The construction defined in claim 2, wherein the upper part is provided with a groove forming a shoulder, said catch comprising a spring tensioned to automatically engage behind said shoulder when the upper part of the cover is rotated sufficiently to project the bolts.

6. The construction defined in claim 2, wherein the upper part is provided with a groove forming a shoulder, said catch comprising a

spring tensioned to automatically engage behind said shoulder when the upper part of the cover is rotated sufficiently to project the bolts, and a finger pin slidable through the upper part and operable for depressing said catch so as to disengage the latter from behind said shoulder and permit rotation of the upper cover part by said spring for releasing the locking bolts.
